UNITED STATES PATENT OFFICE.

EDWIN F. PRATER AND FRED W. SIZER, OF TWIN FALLS, IDAHO.

ROTARY VALVE.

1,194,421.

Specification of Letters Patent. Patented Aug. 15, 1916.

Application filed September 30, 1915. Serial No. 53,444.

To all whom it may concern:

Be it known that we, EDWIN F. PRATER and FRED W. SIZER, citizens of the United States, residing at Twin Falls, in the county 5 of Twin Falls and State of Idaho, have invented new and useful Improvements in Rotary Valves, of which the following is a specification.

The invention relates to rotary valves, and 10 more particularly to the class of rotary valve combustion engines.

The primary object of the invention is the provision of an internal combustion engine of this character wherein the rotary valve 15 employed will take the place of the usual puppet valve in engines of this type, thereby lessening the number of the working parts of the said engine and assuring a more perfect working thereof.

Another object of the invention is the provision of an engine of this character wherein the puppet valves and springs are eliminated, thereby obviating the necessity of considerable grinding of the valves and 25 trouble from corrosion of the same.

A further object of the invention is the provision of an engine of this character wherein the spark plug is so located that the charge is fired in the center of the cylinder 30 of the engine.

A still further object of the invention is the provision of an engine of this character wherein, in the event of the use of a small 35 bored cylinder and the rotary valve, the horse power thereof will be the same as that of the usual type of engine having a larger bore cylinder and the ordinary puppet type of valve.

A still further object of the invention is 40 the provision of an engine of this character which is extremely simple in construction, thoroughly reliable and efficient in operation and inexpensive in manufacture.

With these and other objects in view, the 45 invention consists in the construction, combination and arrangement of parts as will be hereinafter fully described, illustrated in the accompanying drawings, and pointed out in the claim hereunto appended.

In the drawings: Figure 1 is a vertical 50 longitudinal sectional elevation through the engine constructed in accordance with the invention; Fig. 2 is a fragmentary vertical sectional view taken at right angles to the section shown in Fig. 1; Fig. 3 is a sectional view 55 on the line 3-3 of Fig. 1; Fig. 4 is a top

plan view; and Fig. 5 is a horizontal transverse sectional view through the cylinder showing the intake and exhaust manifolds removed. Fig. 6 is a diagrammatic bottom 60 plan view showing the connections between the rotary valves in multiple cylinders.

Similar reference characters indicate corresponding parts throughout the several views of the drawings.

Referring to the drawings in detail, A designates a portion of the cylinder of the internal combustion engine, B the piston reciprocatingly movable therein, C the stem of the said piston; D the crank of the driving shaft E and F the crank chamber formed by the casing G at one end of the cylinder which is separable therefrom, while the said casing G is made in two parts, although it may be otherwise constructed if 75 found desirable. Surrounding the cylinder A is a water jacket H, as usual, which has communicating with its water space a water supply pipe I leading from any suitable water cooling system.

Mounted upon the upper end of the cylinder A is a head J having independent passages in communication with the respective intake and exhaust manifolds K and L, while loosely mounted centrally in the said 80 head is a spark plug M having connection with a suitable electric circuit for the ignition of the charges when admitted and compressed within the cylinder A, the head being formed with a water space N which has 85 communication with a water pipe O leading from the cooling system hereinbefore described.

At the joint between the cylinder A and the crank casing G, interiorly thereof, is formed an annular race-way 10 in which is fitted a beveled gear 11 which has threaded 90 therein the lower end of the rotary valve which comprises a cylindrical body or shell 12 which is co-extensive with the cylinder A and snugly fits interiorly thereof, the outer end being formed with an end wall 13 provided with an arcuate shaped opening 14 adapted for registration with the passages 95 leading to the respective intake and exhaust manifolds, the spark plug M being tapped in the end wall 13 of the body or shell 12 of the valve, and working within the latter is the reciprocatingly movable piston B, as is 100 clearly shown.

Mounted on the crank shaft E is a drive gear 16 which meshes with a companion gear 17

loosely journaled upon a stud shaft or axle 18 mounted in the crank casing G; and this companion gear 17 is formed with a beveled pinion 19 which meshes with the beveled gear 11 in the race-way 10 so that on the turning of the shaft E the valve body or shell 12 will be rotated within the cylinder A of the engine for controlling the fuel supply and the exhaust to and from the said cylinder. Interposed between the gear 11 and the opposite walls of the race-way 10 are bearing balls 20 which minimize friction at this point.

The cylinder head J is independent of the cylinder A and rotary valve body or shell 12 and is held in position by suitable fastenings set in the cylinder A, while fitted in the end wall 13 of the valve body 12 and working against the head end marginally of the opening 14 therein is a packing 21 and formed in the wall 13 and leading from the interior of the valve body 12 to the seat for the said packing is a vent 22 which permits compressed fluid to act upon the packing 21 so as to force the same against the head and thereby assure a fluid-tight joint about the opening 14 in the end wall 13 of the valve body or shell 12 to avoid leakage of the fluid therebetween.

In the operation of the engine, when the piston B is moved on the compression stroke the rotary valve body or shell 12 is positioned to close the opening in its end wall and as the said rotary valve body is rotated a spark is delivered to the spark plug M and transmitted into the cylinder, igniting the charge which has been previously admitted thereto from the intake manifold K through the opening 14 which is uncovered at a predetermined point in the rotation of the valve body and thus causing the driving of the piston B downwardly. The rotary valve body 12 continues its motion and as the piston B arrives at about twenty-five degrees from the down center the opening 14 begins to uncover the exhaust passage so that at the completion of the upward stroke of the piston the burnt gases have been discharged and the exhaust manifold L is shut off by the passing of the opening 14 in the end wall 13 of the valve body beyond the exhaust passage. The rotary valve body 12 continues its motion so that the opening 14 commences to uncover the intake manifold 55 as the piston B starts on the down stroke, remaining open until the crank shaft is approximately ten degrees above down center when the said opening is entirely closed. From this upward, the compression of the charge commences and a high degree of compression is obtained, owing to the large volume of gas drawn into the cylinder. The power for the rotation of the valve is taken

directly from the crank shaft, it being understood, of course, that the gear connections therebetween are thoroughly oiled and, in fact, are maintained in a bath of oil at all times. The gas under compression within the cylinder is forced through the vent 22 to act upon the packing 21 so as to render the joint between the head and the valve body air-tight and this packing perfectly wipes the inner surface of the cylinder head as the valve rotates.

In Fig. 6 there is shown the arrangement of the rotary valves for multiple cylinders, the valves in pairs being fitted with spur gears 23 meshing with each other for the driving of the rotary valves. One gear 23 of each pair is also formed with beveled gear teeth 24 for meshing engagement with a beveled pinion adapted to be driven from the crank shaft of the engine.

From the foregoing description, taken in connection with the accompanying drawings, the construction and manner of operation of the device will be clearly understood, and, therefore, a more extended explanation has been omitted.

Having thus described our invention, we claim:

In an internal combustion engine, a cylinder, a crank case detachably connected with the cylinder, said cylinder and crank case forming a raceway at the juncture thereof, an inner cylinder fitted within the first named cylinder and having an externally threaded end, a beveled gear threaded on the externally threaded end of the inner cylinder and movable in the raceway, the said gear being formed with a central opening corresponding to the size of the core in the inner cylinder, bearing balls interposed between the walls of the raceway and the faces adjacent thereto of the gear, a piston working within the inner cylinder, a crank operating said piston and located in the crank casing, gear connections between the crank and the said gear on the inner cylinder for rotating the same, inlet and exhaust pipes leading from the first named cylinder at the head thereof, a head on the inner cylinder and having openings adapted for alternate registration with the inlet and exhaust pipes, and a spark plug mounted centrally in the head on the inner cylinder and loosely projected through the head on the first named cylinder.

In testimony whereof we affix our signatures in presence of two witnesses.

EDWIN F. PRATER.
FRED W. SIZER.
